UNITED STATES PATENT OFFICE.

OLOF N. BERGMAN AND ALBERT GRAN, OF CHICAGO, ILLINOIS.

INTERMITTENT FOUNTAIN DRAWING-PEN.

1,087,425.

Specification of Letters Patent.

Patented Feb. 17, 1914.

Application filed March 31, 1913. Serial No. 757,983.

To all whom it may concern:

Be it known that we, OLOF N. BERGMAN, a subject of the King of Sweden, and ALBERT GRAN, a citizen of the United States, residing at Chicago, in the county of Cook and State of Illinois, have invented certain new and useful Improvements in Intermittent Fountain Drawing-Pens; and we do declare the following to be a full, clear, and 10 exact description of the invention, such as will enable others skilled in the art to which it appertains to make and use the same.

This invention relates to improvements in fountain drawing pens.

15 One object of the invention is to provide a fountain drawing pen having an improved means for controlling the flow of and positively feeding the ink to the blades or point of the pen.

20 Another object is to provide a pen of this character having means for opening or spreading the blades of the pen to a greater or less extent whereby light or heavy lines may be drawn and having means whereby 25 the position of the parts when adjusted for drawing light or heavy lines is indicated, thus permitting the parts to be readjusted to the same position after having been changed for any purpose.

30 With these and other objects in view, the invention consists of certain novel features of construction, and the combination and arrangement of parts as will be more fully described and claimed.

35 In the accompanying drawings; Figure 1 is a side view of our improved pen with parts broken away; and showing the cap in position thereon and partly in section; Fig. 2 is a central longitudinal section of the 40 pen with the cap removed; Fig. 3 is a side view of the upper end of the barrel or body of the pen with the reservoir removed; Fig. 4 is a similar view taken at right angles to Fig. 3; Fig. 5 is a cross sectional view taken 45 on the line 5—5 of Fig. 2; Fig. 6 is a similar view taken on the line 6—6 of Fig. 2; Fig. 7 is a similar view taken on the line 7—7 of Fig. 2; and, Fig. 8 is a side view of the cap provided to cover the blades of the 50 pen when not in use; Fig. 9 is an enlarged cross sectional view of the blades taken on the line 9—9 of Fig. 2.

55 Our improved pen comprises a handle 1, blades 2, a reservoir 3 and a cap 4 adapted to be engaged with the blades and lower end of the handle of the pen when the latter is

not in use. The handle of the pen comprises a tubular body or barrel 5, the upper end of which is reduced to form an ink cylinder 6 at the inner end of which and at the upper 60 end of the enlarged portion of the body of the handle are formed exterior screw threads 7 adapted to receive the threaded inner end of the reservoir 3 which is engaged with and surrounds the ink cylinder 6 on the upper 65 end of the body of the handle as shown. The body or barrel 5 of the pen is separated from the ink cylinder 6 by a diaphragm or partition 8 having a centrally disposed passage 9 the purpose of which 70 will be hereinafter described. In the opposite sides of the cylinder 6 immediately above the diaphragm or partition 8 are formed ink passages 10 and 11 which communicate with the reservoir 3 and permit 75 the ink therefrom to flow into the cylinder. It will be noted that the passage 10 is longer or extends up a slight distance beyond the upper end of the passage 11 for a purpose hereinafter described. The upper end or 80 shank 12 of the blade is cylindrical and has a revoluble sliding engagement with the lower open end of the barrel or body 5 of the handle and in said shank 12 is a threaded bore 13 the lower or inner end of which 85 communicates with the space between the blades of the pen as shown.

Slidably mounted in the inner end of the cylinder 6 is a combined valve and plunger 14 comprising a pair of disks of suitable 90 material which have a close sliding engagement with the inner walls of the cylinder as shown. The combined thickness of the disks forming the plunger 14 is less than the length of the shorter ink passage 11 in the 95 lower end of the cylinder, so that when the plunger is retracted or disposed in the inner or lower end of the cylinder 6 the ink from the reservoir 3 is permitted to flow into the cylinder above the plunger. The plunger 100 14 is connected in any suitable manner with the outer or upper end of a tubular stem or shank 15 which extends downwardly through the aperture 9 in the diaphragm or partition 8 and through the barrel or body 105 of the pen and the shank 12 of the blades and has its front end disposed between the blades 2 of the pen as shown. At a suitable position on the tubular shank 15 is shrunk or otherwise rigidly secured an exteriorly 110 threaded sleeve 16 having a threaded engagement with the socket 13 in the shank 12.

of the blades 2 whereby said blades may be screwed inwardly or outwardly on said sleeve and by means of which the blades are connected with the shank 15 so that when 5 the blades are pushed inwardly or upwardly into the barrel or body 5 of the handle, the shank 15 and the plunger 14 on the upper end thereof will be projected up in the cylinder 6, thus forcing the ink from said cylinder down through the tubular shank 15 as 10 will be hereinafter more fully described.

In the upper portion of the tubular barrel 5 and a suitable distance from the dia- 15 phragm or partition 8 is arranged a disk or partition 17 between which and the parti- 20 tion 8 is placed a packing 18 of cork or other suitable material. On the upper end of the threaded sleeve 16 is a head 19 be- 25 tween which and the disk 17 is arranged a coiled spring 20 the pressure of which is ex- 30 ereted to project the blades 2 of the pen and to normally hold said blades in a projected position. When the blades are thus pro- 35 jected the tubular shank 15 will also be projected thereby retracting the plunger 14 into the inner or lower end of the cylinder 6 after these parts have been forced up or back into the cylinder 6 as hereinbefore de- 40 scribed.

30 As hereinbefore stated the lower or outer end of the tubular shank 15 extends down- 35 wardly between the blades 2 and on the inner sides of said blades at the lower end of the shank are formed inwardly project- 40 ing beveled or V-shaped blade spreading lugs 21, the upper edges of which when the blades 2 are screwed inwardly on the threaded sleeve 16 are brought into engagement with the end of the shank 15. The engage- 45 ment of the lugs 21 with the end of the shank 15 will spread the blades 2 apart to a greater or less extent for drawing lines of different width. In order that the position of the blades when thus adjusted and the 50 thickness of the lines drawn thereby may be indicated to permit the parts to be re-ad- justed to this position or for drawing lines of the same thickness, an indicating scale 22 is provided, said scale being arranged on the lower end of the barrel or body 5 of the handle. On the shank 12 or inner ends of the blades 2 is an indicating mark 23 which 55 co-acts with the marks on the scale 22 when the blades are turned to screw the same in- wardly on the threaded sleeve 16. By this arrangement it will be seen that when the blades have been adjusted to draw a line of the desired width the position of the mark 23 with respect to the scale 22 is noted, so 60 that when for any reason this adjustment has been changed and it is desired to bring the points back to the same position, it is simply necessary to turn the blades until the mark 23 is again brought to the former 65 position on the scale 22.

Secured in and projecting beyond the inner or lower end of the shank 15 is a tubular cylindrical valve casing 24 which extends downwardly between the lugs 21 which are recessed at their apexes to receive said cas- 70 ing. Arranged in the tubular shank 15 of the plunger 14 is a needle valve 25 the lower end of which projects through the casing 24 and has one side recessed to form an ink dis- 75 charging groove 26 the lower end of which is uncovered when the blades 2 and the shank 15 and plunger 14 carried thereby are pressed upwardly into the barrel of the pen thereby permitting the ink which is forced from the cylinder 6 into the tubular shank 80 15 by the upwardly movement of the plun- gers 14 to be discharged from the shank into the point or between the blades of the pen below the lugs 21 as will be readily under- 85 stood. The upper end of the valve 25 is se- 90 cured in the end of a head 27 which has a close fitting engagement with the upper or outer end of the cylinder 6 and is locked or fastened in said end of the cylinder by means of a locking stud 28 which is adapted 95 to be engaged with and turned in a bayonet slot 29 formed in one side of the cylinder as shown. In the head 27 is formed a trans- 100 verse aperture 30 which is adapted to re- ceive the point of any suitable instrument by means of which the head may be disengaged from the cylinder 6 and the valve drawn out of the tubular shank 15 for clean- 105 ing or other purposes after the reservoir 3 has been removed from the barrel of the pen. 110

As hereinbefore stated the spring 20 nor- mally holds the plunger 14 in the inner or lower end of the cylinder 6 in which posi- 115 tion of the plunger the outer ends of the ink passages 10 and 11 are uncovered so that the ink in the reservoir 3 is permitted to flow into the cylinder 6 which is thus always filled as long as the reservoir 3 con- 120 tains any ink. When it is desired to use the pen, the cap 4 is removed from the blades and the latter, together with the tubular shank 15 and plunger 14 are forced in- 125 wardly by engaging the point of the pen with a fixed surface and pushing down- wardly on the handle or by grasping the blades of the pen and forcing the same in- wardly. The plunger 14 when thus pro- jected forces the ink from the cylinder 6 into and through the tubular shank 15. The inward or upward movement of the tubular shank 15 with the blades 2 also retracts the valve casing 24 and uncovers the lower end of the ink groove or recess in this end of the valve 25 and thereby permits the ink to discharge from the lower end of the shank 15 and valve casing 24 between the points of the blades. As soon as pressure is re- 130 moved from the blades the spring 20 will again project the blades and tubular shank 15 thereby closing the discharge grooves 135

or recesses 26 in the end of the valve 25 and retracting the plunger 14 to the inner or lower end of the cylinder thus again uncovering the ink passages 10 and 11 and permitting more ink to flow into the cylinder 6 from the reservoir. By making the ink passage 10 of greater length than the passage 11 it will be seen that the ink from the reservoir will be permitted to flow more freely into the ink chamber as the air in the cylinder has more opportunity to escape when the ink flows into the cylinder. When the ink has thus been supplied to the blades or point of the pen the latter is ready for use and the blades may be adjusted in the manner described to permit the drawing of light or heavy lines.

In order to prevent the tubular stem 15 of the plunger and the threaded sleeve 16 from turning when the shank 12 of the blades is screwed inwardly or outwardly on said sleeve for opening and closing the blades, the inner disk of the plunger 14 is provided on its lower end with diametrically opposite lugs 14^a which when the plunger and stem are retracted by the spring 20, will engage notches 14^b in the partition 8 or adjacent portion of the barrel 5. In the outer side of the upper disk of the plunger 14 is also formed a notch 14^c adapted to receive a screw driver for screwing the disk onto or off of the stem 15.

The cap 4 preferably has its inner end slotted as at 31 to permit said end to grip the lower end of the barrel or body 5 of the pen and thus obtain a firmer engagement therewith. The outer end of the cap is preferably knurled or roughened to permit a firm grip to be obtained thereon when the cap is removed. The inner end or shank 12 of the blades 2 is preferably provided with longitudinal slits to permit the shank to expand into close engagement with the inner surface of the barrel or body 5 of the pen when said shank is screwed onto the sleeve 16 as hereinbefore described.

From the foregoing description taken in connection with the accompanying drawings, the construction and operation of the invention will be readily understood without requiring a more extended explanation.

Various changes in the form, proportion, and the minor details of construction may be resorted to without departing from the principle or sacrificing any of the advantages of the invention as claimed.

Having thus described our invention, what we claim is:

1. A fountain pen comprising a tubular barrel, a cylinder on one end thereof having ink receiving passages, a reservoir on the rear end of said barrel and surrounding said cylinder, blades having on their inner ends a tubular shank slidably engaged with the front end of the barrel of the pen, an

ink ejecting plunger slidably mounted in said cylinder, a tubular stem connected with said plunger and communicating with said cylinder, means to adjustably connect said blades with said tubular stem, and a valve 70 extending through said stem and operable to control the discharge of the ink from the lower end of said tubular stem between the points of the blades.

2. A fountain pen comprising a tubular barrel, an ink cylinder on the upper end thereof, and having therein ink passages, one of which is of greater length than the other, a reservoir arranged on the outer end of the barrel around said cylinder, blades 80 having a shank slidably and revolvably engaged with the lower end of said barrel, said shank having a threaded socket, a plunger slidably mounted in said cylinder, a tubular stem secured at its upper end to said plunger and opening into said cylinder, a threaded sleeve fixed on said stem and having a threaded engagement with the socket in the shank of the blades, a valve casing in the outer end of said tubular stem, a needle 90 valve arranged through said stem and cylinder and having its lower end engaged with said casing and provided with a discharge groove, a head on the upper end of said valve and adapted to fit the upper end of 95 said cylinder, means to lock said head in the cylinder, and a spring to project the blades of the pen and the parts actuated thereby.

3. A fountain drawing pen comprising a tubular barrel, an ink reservoir detachably 100 engaged with the upper end thereof, blades having a revolute and sliding engagement with the lower end of the barrel, an ink feeding mechanism comprising a plunger having a tubular stem extending downwardly between said blades, a sleeve fixed on said stem and having a threaded engagement with the inner end of the blades, beveled spreading lugs formed on the inner sides of the blades and adapted to be engaged with the end of said stem. 110

4. A fountain pen comprising a tubular barrel having thereon a scale, and on its upper end a cylinder, an ink reservoir surrounding said cylinder and communicating therewith, blades having a revolute and sliding engagement with the lower end of said barrel, an ink feeding mechanism comprising a plunger slidably mounted in said cylinder, a tubular stem connected with said plunger and extending downwardly between said blades, a sleeve fixed on said stem and having a threaded engagement with the inner ends of the blades, spreading lugs formed on the inner sides of said blades and adapted to engage the end of said shank when said blades are screwed inwardly on said sleeve thereby spreading said blades to a greater or less extent, said blades having thereon a mark adapted to co-act with the 120 125 130 135 140 145 150 155 160 165 170 175 180

scale on the barrel of the pen whereby the adjustment of the blades is indicated.

5. A fountain drawing pen comprising a tubular barrel having on its upper end a cylinder, an apertured partition between said cylinder and barrel, said partition having therein notches, an ink reservoir on the upper end of the barrel, blades having a revolvable and sliding engagement with the lower end of the barrel, an ink feeding mechanism comprising a plunger slidably mounted in said cylinder and consisting of a pair of disks having threaded apertures, a plunger operating stem having a threaded engagement at its outer end with said disks, lugs formed on one of said disks and adapt-

ed to engage the notches in said partition, the other disk of said plunger having in its outer end a screw driver slot, a sleeve fixed on said stem and having a threaded engagement with the inner end of said blades, and means whereby the blades are spread for drawing light or heavy lines. 20

In testimony whereof we have hereunto set our hands in presence of two subscribing 25 witnesses.
